UNITED STATES PATENT OFFICE.

HIRAM E. GRIGGS, OF WAYNE, NEBRASKA.

END-GATE.

1,351,165.

Specification of Letters Patent. Patented Aug. 31, 1920.

Application filed December 26, 1919. Serial No. 347,293.

To all whom it may concern:

Be it known that I, HIRAM E. GRIGGS, a citizen of the United States, residing at Wayne, in the county of Wayne and State 5 of Nebraska, have invented certain new and useful Improvements in End-Gates, of which the following is a specification.

My invention relates to end-gates for wagon boxes, and to that class of end-gates 10 formed of two sections hinged together.

My object is to provide an end-gate of this character which, when broken, permits grain to escape into an elevator, the device being arranged to permit the end-gate to 15 open only the proper distance however much the forward end of the wagon box may be elevated, and to hold it secured to the wagon box all the time whether in its opened or closed position, in order to prevent it from 20 at any time becoming accidentally detached from the wagon box, so that if a careless driver forgets to close the end-gate, he is in no danger of losing it as he drives home.

Another object is to provide a device 25 which gives an opening at the middle of the rear end of the wagon box which opening causes the grain to empty into the middle of the dump hole of the elevator, thereby preventing any of the grain from spilling 30 out at the sides of said hole. In this latter respect the device is specially adapted for use with truck bodies which are wider than ordinary wagon bodies, and therefore specially liable to spill out grain at the sides 35 of the dump hole, if provided with the ordinary end-gate.

Still another object is to provide an end-gate of this character which is normally held flush with the rear end of the wagon 40 box, so as to give the largest possible opening in proportion to the distance the hinged sections of the end-gate are moved rearwardly.

Other objects will appear in the subjoined 45 description.

An important feature of the invention consists of a pair of keepers rigidly secured to the sides of the wagon box, and each having a head and neck portion projecting beyond the rear end of the wagon 50 box; a pair of latches coöperating with said keepers, said latches being each loosely pivoted at one end to the end-gate and pro-

vided at the other end with a longitudinal slot for receiving the neck of the keeper, 55 said slot having an opening leading out through the lower side thereof, to permit the slot in the latch to engage the keeper; and angle corner pieces at the rear corners of the wagon box for stops to hold the ends 60 of the end-gate against rearward movement.

The invention consists in the novel construction and arrangement of the several parts, as will be hereinafter described and claimed, reference being had to the accompanying drawings, in which:—

Figure 1 is a broken perspective view, showing an end-gate provided with my improvement. Fig. 2 is a top plan view of the rear portion of a wagon box provided with 70 my improvement. Fig. 3 is a plan view of one of the keepers; and, Fig. 4 is a similar view of the pivoted latch coöperating therewith.

The numerals 1 and 2 indicate the bottom 75 and sides respectively of a wagon box, which is provided with an end-gate formed in two sections 3 and 4 connected together by hinges 5. The section 3 carries a latch-board 6 rigidly secured thereto, and the section 4 a rotatable latch 7 adapted to co-operate with the latch-board 6 by means of the slot 8 at the free end thereof, to lock the parts of the end-gate together in their normal position on the wagon box. 85

The wagon box is provided at its rear corners with angle irons 9 which are formed preferably of steel. The broader sections 9^a of these angle irons are rigidly secured to the sides 2 of the wagon box with the narrower sections 9^b lapping the ends of said sides and projecting inwardly beyond the same. 90

At the rear inner corners of the wagon box are the vertical cleats 10, rigidly secured to the sides 2 of the box and spaced from the rear ends of said sides a distance approximately equal to the thickness of the material used in making the sections 3 and 4 of the end-gate. 95

When the end-gate is in its normal closed position as illustrated in Fig. 1 of the drawings, the free ends of its sections 3 and 4 are received between the cleats 10 and the sections 9^b of the angle irons. That is to 100 say, each section 9^b takes the place of one of

the ordinary wooden cleats usually employed for holding the end-gate in place; but with the difference that the present arrangement holds the end-gate flush with the 5 rear end of the bottom 1 of the box, whereas with the ordinary arrangement, employing two wooden cleats, the end-gate is held on the bottom about two inches inwardly from the end thereof.

10 For a dumping wagon, my present arrangement has the very decided advantage of giving the largest possible dump-opening when the sections 3 and 4 of the end-gate are moved rearwardly a given distance. In 15 addition to this, wooden cleats when frequently subjected to sudden and heavy strains soon work loose and become unreliable, to say nothing of the fact that they are easily affected by moisture and will soon 20 begin to rot when exposed to the weather.

In addition to the above, the angle irons 9 also coöperate with important features, now to be described, in a way to produce most desirable results, when the end-gate is 25 broken for any reason either intentional or accidental.

The keepers 11 are rigidly secured to the sides 2 of the wagon box, preferably on the sections 9^a of the angle irons, and have their 30 head and neck portions 11^a and 11^b respectively projecting rearwardly beyond the angle irons. The corner latches 12 which coöperate with these keepers 11 are provided at their inner ends with bores 13 and at 35 their outer ends with longitudinal slots 14 having openings 15 leading out through their lower sides. By means of the bores 13 these corner latches are loosely pivoted to the sections 3 and 4 of the end-gate, and 40 the necks 11^b of the keepers are adapted to be received into the slots 14 through the openings 15. At the inner ends of the corner latches I provide the washers 16, and the free ends 12^a of these latches may be 45 curved outwardly if desired, as illustrated in Fig. 2, though they also work well when perfectly straight.

In operation, my end-gate when in its closed position, as illustrated in Fig. 1, is 50 held in this position in the ordinary way by means of the latch 7, with the ends of the end-gate received between the cleats 10 and the rear sections 9^b of the corner angle irons. When in this position, the keepers 55 11 and the coöoperating corner latches 12 are practically idle, though, of course, they would prevent the end-gate from being moved upwardly if that were attempted. It will be noticed that the arrangement of 60 the parts is such that the corner latches 12 cannot be disengaged from the keepers 11 till the latch 7 has been operated to release the free end of the latch-board 6 from the 65 section 4 of the end-gate, and the end-gate moved rearwardly sufficiently to bring the

openings 15 of the corner latches 12 into vertical registration with the keepers 11. That is to say, there is only one position of the end-gate in which the corner latches can be disengaged from their keepers, and that 70 position is between the closed position of the end-gate and its farthest open position.

When it is desired to dump a load of grain into an elevator, and the rear end of the wagon box has been brought over the 75 elevator hole, and the front end of the box elevated, the end-gate is then unlatched by a proper turn of the latch 7; the rearward pressure of the grain will now open the end-gate bringing the parts into the position illustrated in Fig. 2, with the widest point in the dump-opening exactly at the middle of the wagon box. The latches 12 will not permit the end gate to open only so 80 far, no matter how great the pressure of the grain against it, or how suddenly it may have opened when the latch 7 was operated.

With ordinary end-gates, there is danger at this point of the end-gate being jerked 85 out of the hand of the operator, and carried 90 down through the elevator hole with the grain.

As the outer ends of my end-gate are held between the cleats 10 and the sections 9^b of the angle irons, the end-gate cannot rock 95 up and down at its middle portion but is held rigid, as it were, against such movement, and always substantially at right angles to the plane of the bottom of the wagon box.

100 My device does not open the whole rear end of the wagon box, but only a certain predetermined portion at the center thereof, so that it always causes the grain to run into the middle of the elevator hole, and 105 does not permit such a wide flow of grain from the box as to scatter it at the sides of the hole where it would have to be swept in with a broom after the load had been dumped from the wagon. For this reason, 110 my device is specially adapted for use with truck bodies which are wider than wagon bodies.

115 From the foregoing it will be seen how greatly superior my device is to the ordinary end-gate which has to be entirely removed from the wagon box when grain is to be dumped into an elevator.

Again attention is called to the fact that the corner latches 12 cannot accidentally 120 become disengaged from the keepers 11 when the end gate is broken (*i. e.*, open), as illustrated in Fig. 2; and therefore if a careless driver forgets to close the end-gate after a load has been dumped into the elevator, he can nevertheless drive on home 125 without the least danger of losing his end-gate.

130 From the foregoing, it becomes apparent that I have produced an end-gate of supe-

rior merit and of great practical value, as I have fully proved, having thoroughly tried out the device in practical use.

Having thus described my invention, what I claim as new and desire to secure by Letters Patent is:—

1. In a device of the character described, the combination with the sides and bottom of a wagon box, of an end-gate hinged between its ends to open rearwardly; spaced cleats on the sides of the box for engaging the free ends of the end-gate sections to hold them against lateral movement while permitting them to move toward each other 10 when the end-gate is opened rearwardly; rearwardly projecting keepers secured to the sides of the wagon box; corner latches pivoted at their inner ends to the hinged sections of the end-gate, and provided at 15 their outer ends with means for engaging and disengaging said keepers, said means including longitudinal slots in engagement with said keepers to permit longitudinal movement of the latches on the keepers for 20 permitting the sections of the end-gate to move toward each other when opened rearwardly without becoming detached from the 25

sides of the wagon box; and means for securing the end-gate sections in rigid relation to each other.

30

2. In a device of the character described, the combination with the sides and bottom of the wagon box, of an end-gate hinged between its ends to open rearwardly; spaced cleats on the sides of the box for engaging the free ends of the end-gate sections to hold them against lateral movement while permitting them to move toward each other as the end-gate is opened; rigid keepers projecting rearwardly from the sides of the 35 wagon box with the projecting portions of said keepers having reduced neck portions; corner latches pivotally secured at their inner ends to the end-gate sections, and provided at their outer ends with elongated 40 openings adapted to removably engage the necks of said keepers, said openings being elongated to permit a limited movement of the end-gate sections toward each other when the end-gate is opened rearwardly; and 45 means for securing the end-gate sections in 50 rigid relation to each other.

In testimony whereof I affix my signature.

HIRAM E. GRIGGS.
